US0D1065417S

(12) **United States Design Patent** (10) Patent No.: **US D1,065,417 S**
(45) Date of Patent: ** Mar. 4, 2025

(54) **RETICLE**

- (71) Applicant: **Crimson Trace Corporation**, Columbia, MO (US)
- (72) Inventors: **Tim Meissen**, Columbia, MO (US); **William A. Planck**, Columbia, MO (US); **Michael Lindsay**, Columbia, MO (US); **Brian Steere**, Columbia, MO (US); **Michael Cottrell**, Ashland, MO (US); **Ryan Donahue**, Columbia, MO (US); **Cale Johanning**, Moberly, MO (US); **Shane Ball**, Columbia, MO (US)
- (73) Assignee: **Crimson Trace Corporation**, Columbia, MO (US)

(**) Term: **15 Years**(21) Appl. No.: **29/790,975**(22) Filed: **Dec. 23, 2021**(51) LOC (15) Cl. **22-01**
